LOOM FOR WEAVING CORD-TIRE FABRICS.

1,421,081.

Specification of Letters Patent. Patented June 27, 1922.

Application filed October 12, 1921. Serial No. 507,283.

To all whom it may concern:

Be it known that I, FREDERICK C. HALL, a citizen of the United States, residing at Pawtucket, in the county of Providence and 5 State of Rhode Island, have invented certain new and useful Improvements in Looms for Weaving Cord-Tire Fabrics; and I do hereby declare the following to be a full, clear, and exact description of the invention, 10 such as will enable others skilled in the art to which it appertains to make and use the same.

The invention relates to looms for weaving cord tire fabric.

15 Cord tire fabric consists of comparatively heavy warp threads or cords bound together by very fine and weak filling threads which are widely separated and serve merely to retain the cords in close parallel relation.

20 In rubberizing this fabric preparatory to incorporating it in tires it is subjected to the action of heavy calender rolls to which it is fed under heavy tension. Owing to the 25 weakness and wide spacing of the fine filling threads the action of the rolls will cause any comparatively loose cords or series of cords to creep along the fabric and bank up at the point where the fabric enters the rolls until sufficient slack accumulates to 30 cause a fold which will enter the rolls and cause a rupture of the fabric at this point. Comparatively slack cords or zones of slack cords in the fabric are therefore not only 35 highly objectionable but may render a piece of fabric wholly unfit for use. While looseness or under tension of the cords is objectionable in any part of the fabric it is more serious toward the center than at the edges since the center is better adapted to 40 tribute and withstand the extra strain to which those parts of the fabric in which the tension of the cords is up to standard are necessarily subjected in case of looseness in other parts of the fabric.

45 For the above reasons it has heretofore been the ultimate aim of manufacturers of cord fabric to weave a fabric in which the cords are under the same uniform tension throughout the width of the fabric and they 50 have striven to this end with varying degrees of success. I have found, however, that a fabric in which the cords in the center are tighter than the cords in the edge portions is superior to the fabric heretofore con-

sidered ideal and is better adapted to meet 55 the requirements incident to its rubberization and incorporation in tires. I have also found that a slight progressive increase in the tension of the cords from each edge towards the center gives the best results. 60 When a fabric of this character is led from the supply roll to the rubberizing calender rolls under a slight tension the center will be taut while there will be a slight and gradual droop or ruffling toward the edges. 65 Upon an increase in the tension, however, this will disappear as the center cords are stretched and the fabric will lie flat and taut from side to side and will run uniformly and smoothly to the rolls. Owing to the 70 tight center and the decrease in the tension of the cords toward each edge the strain on the fabric due to the tension under which it is fed to the rolls is so distributed across the 75 fabric that the greater strain comes on the stronger center while the least strain comes on the weaker edges. The fabric may, therefore, not only be maintained in a smooth flat condition with less tension than heretofore, but the danger of breaking cords at the 80 edges and thus causing the fabric to tear across is eliminated.

The weaving of this fabric involves the accurate regulation of the tension on each warp cord entering the successive sheds so 85 that the tension on each cord may be uniform throughout the weaving and so that the tension of the different cords may increase from the edges toward the center. The requisite accurate regulation of the ten- 90 sion on each warp cord may be secured by feeding in to the shed forming harness a definite and uniform length of each cord during each cycle of the loom which bears a definite relation to the length of movement 95 of the fabric take-up mechanism. To insure a uniform tension on each warp cord throughout the weaving a pre-determined and substantially uniform tension is maintained on each cord to be fed in. 100

A loom adapted for the production of the tight center fabric is indicated diagrammatically in Fig. 1 of the drawings; Fig. 2 is a side elevation partly in section of the loom, Fig. 3 is a plan view showing the mechanism for actuating the feeding in roll and Fig. 4 is a detailed view of the feeding in roll.

In weaving the fabric upon the loom indicated in the drawings the warp cords are led from the spools 6 through suitable guides in eye-boards or reeds 8, from which 5 they pass alternately over and under a set of leash rods 10 and are thus brought into position side by side. From the leash rods the cords pass to a second set of leash rods 12 and thence between the thin plate of a 10 reed 14 which keep them properly separated and spaced and direct them side by side to the feeding-in mechanism. A substantially uniform tension is maintained on the cords leading to the feeding-in mechanism by 15 take-up weights suspended on the cords and guided in the plates 18 and 20. The weights play freely through the guide plates, thus taking up any temporary slackness which might otherwise occur between the supply 20 spools and the feeding-in mechanism and maintain a substantially uniform light tension on each of the cords. The cords are, therefore, uniformly taut when engaged by the feeding-in mechanism and will be uniformly 25 acted on thereby.

The feeding-in mechanism comprises a feeding-in roller 22 which may be covered with sand or otherwise roughened to prevent slipping of the cords thereon and two cooperating guide rolls 24 and 26 which cause the cords to wrap nearly around the roll. The cords lead from the roll 26 through a reed 27, through the usual leash rods 29 to the harness 4. From the harness the cords pass 30 through the lay 2 to the previously woven fabric which passes over the breast beam 28, around the fabric take-up drum 30, over guide rolls 32, 34 and 36 to the cloth roll 38 upon which it is wound.

40 The feeding-in roll is positively driven to feed forward a definite length of each warp cord and its actuating mechanism is so timed and proportioned with relation to the actuating mechanism of the fabric take-up drum that each warp cord is held under a predetermined tension between the feeding-in roll and the already woven fabric during each cycle of the loom. Since the warp cords are uniformly taut as they come to 45 the feeding-in roll and are positively held and controlled thereby each thread will be under a certain tension between the woven fabric and the feeding-in roll determined by the relation between the movements given 50 to the feeding-in roll and to the fabric take-up drum. If the feeding-in drum is of the same diameter throughout its length and the take-up weights 16 are proportioned to maintain substantially the same light tension on 55 all of the cords leading to the roll equal lengths of all cords will be fed in by the roll for the formation of each shed and a fabric will be produced in which the cords are under the same uniform tension throughout the 60 width of the fabric. In order that the cen-

ter cords may be held under greater tension than the edge cords during each pick of the loom it is preferred to so shape the roll 22 that it feeds in lengths of cord which are slightly less at the center than at the edges, 70 the variation in the lengths of cords being well within their elastic limits. To secure a gradual decrease in the feed from the edge of the fabric toward the center and consequently a gradual increase in the tension of 75 the cords from the edges toward the center the roll is preferably so shaped that it is slightly smaller in diameter at the center and gradually increases in diameter toward each end as indicated in Fig. 4. With the 80 roll thus shaped a fabric will be produced having a tight center and one in which there is a slight progressive increase in the lengths of the cords from the center toward each edge. Consequently there will be a 85 progressive increase in the tension on the cords from the edges toward the center when the fabric is led to the rubberizing calender rolls and is stretched sufficiently to put all of the cords under tension with the resulting 90 advantages already set forth.

The rotation of the feeding in roll is preferably intermittent and so timed that there is no feed of the threads during the passage of the shuttle through the sheds formed by 95 the harness. As shown the feeding in roll is connected through gearing 40 with a ratchet wheel 42, which is engaged and actuated by a pawl 44 connected with the eccentric strap 46 engaging an eccentric 48 carried by the 100 lay operating shaft 50. The eccentric strap is formed on the end of a link 52 connected to the lever 54, which carries the pawl 56 for actuating the ratchet wheel 58 on the end of the cloth shaft 38. The fabric take-up 105 drum 30 is continuously driven through gearing 60 connecting the drum with a worm wheel 62, which is engaged by a worm 64 on a shaft 66 driven through beveled gears 68 from the cam shaft 70 of the loom. 110 The worm and worm wheel drive insures a uniform pull on the fabric and also positively holds the drum against reverse movement under the tension on the fabric and warp threads.

115 What is claimed is:

1. In a loom for weaving cord tire fabric the combination with the harness and lay of mechanism for feeding from the warp thread supply to the harness for each shed 120 lengths of warp threads which progressively increase from the center of the fabric toward the edges and for taking up the fabric to hold all the warp threads in each shed under tension.

125 2. In a loom for weaving cord tire fabric the combination with the harness and lay of an individual supply from which each warp thread is drawn, and mechanism for feeding from the thread supplies to the harness for 130

- each shed lengths of warp threads which progressively increase from the center of the fabric toward the edges and for taking up the fabric to hold all the warp threads in 5 each shed under tension.
3. In a loom for weaving cord tire fabric the combination with the harness and lay of mechanisms for feeding in to the harness for each shed lengths of warp threads which 10 progressively increase from the center of the fabric toward the edges, and for taking up a uniform length of fabric.
4. In a loom for weaving cord tire fabric the combination with the harness and lay of 15 mechanism uniformly feeding in to the harness for each shed a definite length of each warp thread, the length of different threads fed in progressively increasing from the center toward the edges of the fabric, and mechanism 20 for taking up a uniform length of fabric for each shed.
5. In a loom for weaving cord tire fabric the combination with the harness and lay of an individual supply from which each 25 warp thread is drawn, a feeding in mechanism for positively holding all of the warp threads between the thread supply and the harness throughout the weaving and for feeding in lengths of threads which progressively 30 increase from the center toward the edges, and mechanism for actuating the feeding in mechanism to feed in a definite length of each warp thread for each shed.
6. In a loom for weaving cord tire fabric the combination with the harness and lay of 35 a feeding in roll, the diameter of which gradually increases from the center toward each end, means for directing the warp threads side by side to the roll and from the roll to the harness, and mechanism for actuating the roll to feed a definite length of each warp thread for each shed.
7. In a loom for weaving cord tire fabric the combination with the harness and lay of a feeding roll about which all of the warp 40 threads wrap, the diameter of which gradually increases from the center toward each end, guides for directing the threads side by side to the roll and from the rolls to the harness, mechanism for actuating the roll to 45 feed in a definite length of each warp thread for each shed, and a fabric take-up mechanism for taking up a definite length of fabric during each cycle of the loom.
8. In a loom for weaving cord tire fabric 50 the combination with the harness and lay of a feeding-in roll, the diameter of which gradually increases from the center toward each end, means for equalizing the tension on the warp threads and directing them side 55 by side to the roll, means for directing the threads from the roll to the harness, mechanism for actuating the roll to feed in a definite length of each warp thread for each shed, and mechanism for taking up a definite length of fabric during each cycle of 60 the loom.

FREDERICK C. HALL.
